UNITED STATES PATENT OFFICE

134,832

DESIGN FOR A COMBINED CASING COVER AND HANDLE FOR AN ELECTRIC SWITCH

Clifford Brooks Stevens, Fox Point, Wis., assignor
to Cutler-Hammer, Inc., Milwaukee, Wis., a cor-
poration of Delaware

Application December 3, 1941, Serial No. 104,447

Term of patent 14 years

To all whom it may concern:

Be it known that I, Clifford Brooks Stevens, a citizen of the United States and a resident of Fox Point, in the county of Milwaukee and State of Wisconsin, have invented a new, original, and ornamental Design for a Combined Casing Cover and Handle for an Electric Switch, of which the following is a specification, reference being had to the accompanying drawing, forming part thereof.

Figure 1 is a front elevational view of a com-

bined casing cover and handle for an electric switch, showing my new design.

Fig. 2 is a side elevational view thereof, and

Fig. 3 is an end elevational view of said cover and operating handle.

I claim:

The ornamental design for a combined casing cover and handle for an electric switch, substan-
tially as shown.

CLIFFORD BROOKS STEVENS.
